GOLF BAG CONSTRUCTION

Filed Sept. 5, 1930

INVENTOR.

R. J. BLITCH
BY *Victor J. Evans*
ATTORNEY.

UNITED STATES PATENT OFFICE

RUFUS J. BLITCH, OF SCOTIA, CALIFORNIA

GOLF BAG CONSTRUCTION

Application filed September 5, 1930. Serial No. 479,945.

This invention relates to improvements in golf bag construction.

The principal object of this invention is to produce a bag wherein the clubs may be individually positioned in the bag.

A further object is to produce a bag wherein the clubs are suspended from the head.

A further object is to produce a bag of this character which is simple in construction and economical to manufacture.

A further object is to produce a bag wherein the bag may be of light construction if desired, and yet one which will be sturdy.

A still further object is to produce a bag conforming to all standard practices.

Other objects and advantages will be apparent during the course of the following description.

In the accompanying drawings forming a part of this specification and in which like numerals are employed to designate like parts throughout the same,

Figure 1 is a fragmentary side elevation of my bag showing a club positioned therein.

Figure 2 is an enlarged top plan view of my bag, and

Figure 3 is a plan view as the bag would appear in blank form.

It is a well known fact that golf clubs shafts readily warp if they are allowed to rest upon the handles. Further, by providing separate compartments for the clubs, the desired club may be readily selected with a minimum of delay. Further, by having the clubs individually positioned in a bag, their original finish is preserved.

In the accompanying drawings wherein for the purpose of illustration is shown a preferred embodiment of my invention, the numeral 5 designates a bag as a whole which may be made of any desired material, the material being shown at 6 in Figure 3. Reinforcing members 7 are attached to the body of the bag and serves to strengthen the bag from bottom to top. A ring 8 is positioned upon the bag, which ring is formed of relatively thick material, and of relatively wide material. This ring might be termed a doughnut shaped ring, and has formed upon its upper surfaces V shaped recesses 9. Cross

braces 11 and 12 together with a ring 13 serve to form compartments, each compartment being adjacent one of the recesses 9, with the result that the handles of the clubs may be suspended in the compartments, 55 while the head 14 (see Figure 1) rest within one of the V recesses.

It will thus be seen that thru this construction, I have produced a golf bag which has all of the objects above set forth.

It is to be understood that the form of my invention herewith shown and described is to be taken as a preferred example of the same and that various changes relative to the material, size, shape and arrangement of parts 65 may be resorted to without departing from the spirit of the invention or the scope of the subjoined claims.

Having thus described my invention, I claim:—

1. In combination with a golf bag of a doughnut shaped ring secured thereto, said ring having angularly disposed recesses formed therein for the reception of the heads of golf clubs suspended in said bag. 75

2. In combination with a golf bag of a plurality of cross pieces secured to one end of said bag, a doughnut shaped ring mounted on said cross pieces, said ring having angularly disposed recesses formed therein, said 80 recesses being interspaced between said cross pieces.

In testimony whereof I affix my signature.

RUFUS J. BLITCH.
